RENEWABLE BRUSH

Basil E. Jones, Flossmoor, and William H. Peterson, Chicago, Ill.

Application April 10, 1948, Serial No. 20,216

2 Claims. (Cl. 15—223)

1

This invention relates to brushes commonly used in the application of paints, varnishes, lacquers, glue and the like and has for its primary purpose the provision of a renewable brush including a relatively permanent retainer and an expendable, readily replaceable filler element.

The principal object of the invention is the provision of a brush combining a permanent retainer, which may include a handle, with a renewable filler element comprised of paper.

An important object of the invention is realized in the provision of an expendable brush element comprised of a block of paper adapted to be folded intermediate its length and turned back upon itself to provide in that one operation an enlargement for insertion in and retention by a holder and oppositely tapering surfaces at the working edge of the brush.

Another object of the invention is the provision of a brush element comprised of a block of paper which may be slit through its full depth at intervals throughout its width to provide a plurality of strands.

A further object of the invention lies in the provision of a brush element comprised of a block of paper shaped to provide a working edge having oppositely tapering surfaces and a retaining edge of enlarged dimensions.

The foregoing and other and more specific objects of the invention are attained by the arrangement illustrated in the accompanying drawings, in which

Fig. 1 is a general perspective view of a retainer, including a handle adapted to receive a removable brush filler element which may be inserted therein and designed to exert a clamping action on the filler, and including an open channel-shaped way having a restricted throat defined by the opposed flanges of the retainer;

Fig. 2 is a perspective view of the renewable brush filler element comprised of a plurality of sheets of paper in the form of a block folded over at the middle to provide an enlarged tubular portion adapted to be inserted into the retainer and to taper the working edge in opposite directions, and illustrating fastenings adjacent the enlarged retaining portion for maintaining the assembly of the block, and illustrating through slits at intervals across the width of the element providing a plurality of strands;

Fig. 3 is a general perspective view of the brush element and retainer handle showing them in partially assembled relation illustrating the method of assembling the parts by inserting the enlarged retaining portion of the filler element into the

2

open channel-shaped retainer through one end thereof and sliding it into position against the frictional resistance offered by the clamping action of the flanges comprising the channel;

Fig. 4 also is a perspective view of the brush filler element and retainer handle, but showing them in fully assembled relation, with the paper filler element inserted to its final position between the opposed flanges of the channel retainer and which relationship is maintained solely by the flexible gripping action of the retainer flanges;

Fig. 5 is a perspective view of an assembled paper filler element of modified form comprised of a block of unslotted paper affording a plain pad having oppositely tapered working edges and secured by through fastenings adjacent the opposite end of the pad, and having a core member serving as a spreader for the paper sheets to provide a rigid enlargement for positive engagement with the retainer;

Fig. 6 is a detail perspective view of the rectangular pad of paper of which the brush filler element is comprised, shown in the flat before folding, cut to size and slotted at opposite sides of the medial portion, with all edges square;

Fig. 7 is a detail perspective view also of the pad of paper illustrated in Fig. 6, during the folding operation, illustrating the manner of automatically providing the oppositely tapering surfaces of the working edge of the brush by the folding of a pad of equal sized sheets of paper intermediate their length; and

Fig. 8 also is a detail perspective view of the completed block of paper, comprised of the pad illustrated in Figs. 6 and 7 folded back upon itself and secured by through fastenings adjacent the folded portion defining the enlargement for insertion into the holder, with the oppositely tapering surfaces of the working edge disposed upright.

The invention contemplates a brush having a renewable filler brush element which makes feasible a permanent holder having a disposable brush portion which may economically be discarded after each use and replaced by a new filler element.

In the drawings, 10 represents a brush holder of relatively permanent nature, having an upright handle 11 and including a generally channel-shaped brush retainer portion 12. The retainer 12 is formed on a radius terminating in oppositely disposed flanges 13. The flanges are each formed on a compound curve providing a restricted throat and a flaring mouth opening downwardly. The way provided by the channel-shaped retainer is open at both ends to permit

full utilization of the flexibility of the flanges 13 throughout the full length of the retainer, frictionally to engage and grip a removable brush element hereinafter to be described. The channel way may be of any length desired, depending upon the size of the brush to be provided, and while an upright handle has been provided in the form illustrated, any type of handle necessary to any particular form of brush may be provided, as desired, or the handle might be made removable if preferred.

The retainer 12 is designed to receive and closely embrace a removable brush element 15 which, in accordance with the invention, is of a particular form comprised of a material enabling manufacture of the brush as a disposable refill unit for the holder at a cost which would justify the economy of such an arrangement. As shown in Figs. 2, 3 and 4, the brush 15 comprises a block of paper secured by fastenings 16 and having an enlarged end portion 17 adapted to be engaged within the retainer 12. The working edge of the brush is provided with oppositely tapering surfaces 18 to facilitate the application of material to a surface being treated. A plurality of regularly spaced vertical slits 19 extending through the full thickness of the brush may be disposed substantially throughout the area thereof to divide the brush into a plurality of strands 20.

The block of paper 15 preferably is assembled with the holder 10 by slidably inserting the enlarged end portion 17 of the block into the channel-shaped way 12, as shown in Fig. 3, and sliding it axially to the fully enclosed position indicated in Fig. 4, against the friction created by the clamping action of the flanges 13, which retains the brush element in operative position although the block might be snapped into position by forcing it between the flanges against the spring action thereof. Thus assembled, the brush may be used for any purpose desired and then, if necessary, the filler element may be removed by sliding it through either end, and discarded, to be replaced by a new filler for subsequent operations. The economy of the paper filler element makes feasible the full utilization of this disposable feature and frequent replacement by a new element as necessitated by the various types of work for which the brush may be used.

The paper block 15 is comprised of a plurality of sheets of paper of a flexible or pliable nature and which may be stacked in the form of a flat pad 21, as shown in Fig. 6, and cut to the desired size as necessitated by the size of the brush element required to provide the desired flexibility in the brush necessary to proper spreading out and working of the fluid materials with which the brush is designed to be used, such as the application of paints, varnish, glue or the like to wood or metal surfaces or in the general application of liquid materials to any type of surface. The pad may be slotted, as indicated, at opposite sides of the mid-portion in this one cutting operation if the slits 19 are to be provided in the finished article. The individual paper sheets comprising the pad are all cut to the same size, and as a consequence, the folding of the pad about the unslotted mid-portion, as shown in Fig. 7, causes a tapering of the opposite extremities of the pad as it is folded to provide the oppositely tapering surfaces 18 at the working edge of the brush in the completed assembly, as illustrated in Fig. 8. Fig. 7 shows the pad of paper 21 partially folded, while Fig. 8 shows it completely rebent upon itself to provide the block of

paper comprising the renewable brush. The finished state of the brush element is maintained by then inserting staples 16 through the combined thicknesses of the folded pad adjacent to the intermediate folded portion, and this location of the securing means defines the enlargement 17 for confinement in the holder. The folding of the pad and the attachment of fastening means adjacent thereto forms a substantially tubular enlarged end portion well adapted to axial insertion into the open channel-shaped way of the retainer and for retention in the restricted throat therebetween, held firmly in operative position by the pressure exerted through the flexibility of the retaining flanges. The length of the sheets of paper from which the block is formed is such as to afford sufficient length in the finished brush element in proportion to its thickness to provide ample flexibility of the brush in spreading and working out the materials with which it is used.

The block of paper comprising the brush filler element may be fabricated as shown in Fig. 5 if desired. In this arrangement, plain sheets of paper are utilized to provide a block of paper 25, secured adjacent one edge by staples 26 to provide an integrated assembly adapted for insertion into a holder in the same manner as that previously described. A wedge-shaped core member 27, which also might be of paper, may be secured in the block at the stapled edge to provide a well defined enlarged edge portion for positive engagement within the retaining member. As shown, the brush is provided with oppositely tapering surfaces 28 at the working edge, as in the previous form described. In the form shown in Fig. 5, the plain paper sheets afford a brush well adapted to the even application of materials to a surface without streaking, and in all forms the oppositely tapering working edges provide capillary surfaces functioning efficiently to take up and retain the materials used for application to the surface being worked.

From the foregoing, it will be seen that a brush has been provided wherein a relatively permanent holder may be equipped with a replaceable brush which may be renewed indefinitely, and which is comprised of paper for disposability, and of simple formation capable of ready and economical manufacture for low cost distribution.

What is claimed is:

1. A brush for the application of liquid materials required to be worked and spread out over a surface to be coated including an elongated channel shaped holder having a handle extending from the rear thereof substantially midway along the length thereof and a separate brush element mounted in the holder and removable therefrom for renewability, said brush element consisting of a plurality of sheets of paper all of substantially the same length folded in the center and rebent to provide a pad including a flat portion having a working length in proportion to its thickness providing flexibility in the flat portion affording the pliancy thereof necessary to said working and spreading of said materials and terminating in a free edge of V-shape in cross section and having an enlarged tubular portion at the fold, and fastening means securing said sheets together between the tubular and flat portions, said tubular portion being mounted in the channel of said holder.

2. A brush as claimed in claim 1, in which the sheets of paper are slotted lengthwise in the flat

portion only of the pad to divide the sheets into a plurality of strands which are held together by the unslitted portions of the sheets in the tubular portion of the pad and by the fastening means.
